UNITED STATES PATENT OFFICE.

DAVID SOLOMON ELLIS, OF NEWTOWN, NEW SOUTH WALES, AUSTRALIA.

TELEPHONE REGISTER.

Application filed February 24, 1923. Serial No. 621,031.

To all whom it may concern:

- Be it known that I, DAVID SOLOMON ELLIS, subject of the King of Great Britain and Ireland, residing at 32, Wellington Street, 5 Newtown, in the State of New South Wales, Commonwealth of Australia, have invented new and useful Improvements in Telephone Registers, of which the following is a specification.
- 10 The invention has been designed for the purpose of automatically registering, de-registering, or counting each effective call made from telephones and has further been designed to form an addition to and to work 15 in conjunction with the usual type of common battery, manual and automatic sub-station (i. e. subscriber's) apparatus. The underlying object is twofold, viz:—(1) to provide a means whereby the telephone department or company will be paid in advance by users and (2) that users can only be charged for effective calls or in other words cannot make an effective call without such call is registered, de-registered or 20 counted.
- 25 It consists of a combination key and meter or mechanical counter, that operates a switch control connecting (1) the calling circuit (2) the receiver circuit and (3) the transmitter circuit. The special construction of the key and counter and associated apparatus is such that the transmitter and the receiver circuits can only be established immediately after the registration, de-registration or counting of the call upon the 30 meter or counter.
- 35 The counter will be made of suitable metal and may be in the shape of a circular box, having a lid capable of being securely fastened to the same. Projecting from the outside wall of the box at a suitable point is a specially shaped boss, which constitutes the key, having suitably shaped wards cut thereon.
- 40 The method of connecting the switch control to the telephone lines will vary, according to the class of telephone and to the particular class of service desired and to the particular system adopted in the exchange to which it is to be applied, but in all cases will be such that the connection between the calling party and the called party is assured before he registers, de-registers, or 45
- 50
- records that call upon the meter or counter and immediately after establishes conversational conditions.
- 55 The switch under the control of the key enables circuit functions to be performed which ensure that each effective call is positively de-registered on a crown-toothed 60 wheel until the number of effective calls represented by the capacity of the wheel in question have been made, and also guards against the caller obtaining calls to which he is not entitled, and further under proper 65 conditions enables a caller to obtain free service. In addition as will be made clear later, if a caller is in any doubt as to whether or not he has called the right number, the particular call may be abandoned 70 and a fresh one made provided the caller has not actually de-registered.
- 75 The key-meter is constructed in such a manner that it may be set to register any number of effective calls, from 25 to 3,000 or 80 more and when the predetermined number of calls have been made the internal mechanism is locked so that while it is still possible to insert the key into an associated switch it is impossible to converse with the called subscriber. In order to prevent the use of a fraudulent key-meter an electric-thermostat is introduced into the electrical circuit that is completed within the key-meter to establish conversational conditions 85 between the calling and the called parties immediately after the call has been registered, de-registered or counted upon the meter. The thermostat under normal operating conditions is only required to carry current 90 for a fraction of a second and does not operate its contact, but any sustained current will set up heat in the winding of the thermostat thereby actuating the thermostat 95 so as to break the electrical circuit.
- 96 Means are provided for the purpose of indicating to the user that the calling capacity of the meter is nearly exhausted and when it is totally exhausted.
- 100 In order that the invention may be thoroughly understood a more detailed description will now be given and reference will be made to the accompanying drawings in which:—
- 105 Fig. 1. is a front elevation of one type of automatic telephone with its associated dial-

ling device mounted upon a box in which the switch associated with the key-meter and some of its electrical connections are suitably secured, the face of the switch being secured upon the outer face of the box.

Fig. 2. is a plan view of one side of the key-meter, partly in section the side of the case having been removed in order to show the interior mechanism on that side all parts being in their normal position. In this figure the inner crown toothed wheel has been rotated to a position where a tooth of special shape and size has reached a point lying immediately behind the operating lever which is thereby enabled to lie in a position such that when it is moved by the plunger its extremity will engage both the crown tooth wheels and advance them together.

Fig. 2^a. is a detail plan of portion of the crown toothed wheels and their operating lever, the tooth of special shape and size having passed the lever so that when the latter is again operated by the plunger its extremity will engage with the inner crown toothed wheel only.

Fig. 2^b. is a top plan view of the upper end of the key shown in Fig. 2.

Fig. 3. is a central sectional elevation of Fig. 2. the plunger being in the normal position.

Fig. 4 is a similar view to Fig. 3 but a portion only is shown and certain parts have been removed in order to illustrate the position occupied by the plunger when it is depressed and the electrical contacts operated thereby.

Fig. 5. is a plan of the reverse side of the key-meter, partly in section, portion of the key being broken away and part only of that side of the case being cut away in order to show that certain parts are secured to the cover. This figure illustrates the means adopted for regulating the meter so that it will de-register a predetermined number of calls.

Fig. 5^a. is a detail plan of a portion of the key and meter case showing a colour sighting orifice therein whereby when nearly the full capacity of calls have been de-registered a coloured section within the case will be exhibited as an indication of the fact to the user.

Figs. 6, 7, 7^a. and 8 are perspective views of the key in engagement with portion of the switch, the face and ward plates of the latter having been removed in order to show the means adopted for rotating the barrel of the switch, the key being shown in the position it occupies, when first inserted, when turned to position A (Fig. 1), when turned to dialling position B and when turned to registering and conversing position C respectively. At Figure 8 the key is partly in section in order to show the plunger and its

co-acting part of the switch in the position they assume when the key has been turned to the position illustrated.

Fig. 9 is a perspective view partly in section of one side of portion of the switch, the face and ward plates as well as some of the electrical appliances having been removed for the purpose of more clearly illustrating the remainder.

Fig. 10 is a perspective view partly in section of the reverse side of the switch showing the means by which the switch is locked and rendered inoperative under certain circumstances while a differential relay that carries a set of associated contacts is shown in position.

Fig. 10^a. is a side elevation of the differential relay referred to in the foregoing paragraph showing the associated contacts in their normal position.

Fig. 11 is a central longitudinal sectional elevation of the switch stripped of all its electrical connections. Fig. 11^a. is a similar view of the switch face plate, shown detached from the switch in order to minimize the risk of confusing the parts underlying it.

Fig. 12 is a front elevation of the switch with the face and ward plates removed and a part thereof being shown in section to illustrate the means adopted to prevent the key being turned in the wrong direction.

Fig. 12^a. is a side elevation of Fig. 12.

Fig. 12^b. is a detail side elevation partly in section of the cylinder that carries a shaft that engages in the key when the latter is turned to the conversational position and showing the plunger contacts that project beyond the forward end of the cylinder in order to complete and operate electric circuits within the key.

Fig. 13 is a detail perspective view of the trigger mechanism that locks the switch under certain circumstances and prevents further operation, the parts being shown in the "set" position.

Fig. 13^a. is a similar view to Fig. 13 but the trigger has been moved so as to release the plate spring and enable it to descend and lock the switch.

Fig. 14 is a detailed plan view of portions of the rear of the switch, showing the locking plate spring the "P" set of electric contacts and the manner in which they are mechanically operated.

Fig. 14^a. is a plan view of the "P" set of electric spring contacts as they arrange themselves when they are released by the insertion of the key in the switch.

Figs. 15, 16 and 17 show the cams 88, 89 and 90 respectively in elevation together with the electric spring contacts set A. B. C. associated with and operable by each cam, in their normal position.

Figs. 15^a, 16^a and 17^a. show, respectively the cams 88, 89 and 90 in elevation together

with the electric spring contact sets associated with each cam the cams and the sets of contacts being shown in the positions they will occupy when the key 21 has been turned 5 to the respective positions shown at A. B. C. (Fig. 1) in succession when calling a number.

Fig. 18 is a schematic circuit showing the arrangement of the various circuit conditions when the invention is applied to a 10 telephone, which is to work on a "Strowger" (Automatic Electric Company, Chicago,) full automatic system.

The key-meter or counter consists of a 15 shallow circular shaped metal box 20 in which the recording mechanism is housed. The box is provided with a boss 21 that constitutes the key and which is provided with an orifice 22 cut longitudinally therein and 20 also through the wall of the box to enable a specially shaped plunger 23 to normally slide back and forth therein. Axially within and upon the base of the box 20 is a circular shaped shouldered boss 24. Mounted 25 upon the boss 24 is a specially shaped locking arm 25 that acts as a distance piece and for a purpose to be hereinafter explained. Rotatably mounted upon the boss 24 above the locking arm 25 are two discs 30 or wheels 26 and 27 provided respectively with crown teeth 28 and 29. The wheel 26 is of a larger diameter than the wheel 27 and the teeth 28 are deeper than the teeth 29 to enable the latter to lie concentrically 35 within and adjacent to the teeth 28, each set of teeth being capable of rotation with their respective wheel independently of each other. The plunger 23 is undercut at 23^a the inner end being bent downwardly at 23^b 40 and the extremity forked so as to enable the forked end of the plunger 23 to slide radially upon the inner face of the wheel 27, the tines of the fork sliding upon diametrically opposite sides of the boss 24. 45 In order to return the plunger 23 to its normal position a hole 30 is bored transversely through the plunger; through this hole, a bow spring 31 is passed, the ends of such bow spring normally lying in a recess 32 50 cut in the inner face of the side wall of the box 20.

The inner end of the boss 24 is drilled and tapped to receive a screw 33 the function of which is partly to retain certain 55 parts in position and partly to provide a means for carrying other parts. A flat plate spring 34 passes diametrically across and within the box 20 above the fork, the radii of such spring being of different 60 lengths so that one end rests upon one or more of the crown teeth 28 upon the outer wheel 26 while the other end rests upon the teeth 29 upon the inner wheel 27 in order to frictionally retain the wheels in position 65 after each movement. Secured to the un-

derside of the plunger 23 by the screws 35 is a bent lever arm 36 to which is articulated, by means of knuckle joint 37, a lever 38 that is adapted to engage with one of the teeth 29 and move it and the wheel 27 to 70 their next successive position every time the plunger 23 is moved radially inward.

Each tooth 29 on the wheel 27 except 29^a is slightly in advance of the adjacent tooth 28 of the wheel 26, and this tooth 29^a 75 is smaller than the others in order to allow the articulated lever 38 an extended movement once in every revolution of the wheel 27 so that it will engage both wheels 26 and 27 and move them together onward one 80 tooth. In order to keep the lever 38 normally in engagement with the teeth 29 on the wheel 27 a slot 39 is cut in the bent lever arm 36 and another in the lever 38, the ends of a bent plate spring 40, being sprung 85 into these slots so as to force the lever outwardly. A small metal plate 41 is rigidly secured to the bent lever arm 36 by screws 42 one end of such plate projecting across the knuckle joint 37 lies upon the lever 38 90 so as to prevent the latter from becoming disengaged from the bent lever arm 36.

Returning now to the central screw 33, a short strip of metal 43 having a perforation through which the screw 33 passes projects outwardly from the centre in an opposite direction to the plunger 23; to this metal plate 43 a T-shaped piece of electrical insulation material 44 is secured in any suitable manner to form a base upon which to 95 mount an electro thermostat 45. Mounted upon the screw 33 above the plate 43 are two spring contact pieces 46 and 47 suitably insulated from one another and from other parts by the insulating discs 48, 49 and 50, 100 and insulating material 50^a and 50^b, the flat head 33^a of the screw pressing firmly upon the insulating disc 50 in order to hold the various parts rigidly in position when the screw 33 is screwed home. 110

The spring contact pieces 46 and 47 have tail pieces 51 and 52 respectively, a lead 53 being connected to the piece 51 and another lead 54 being connected to the piece 52. The lead 53 is connected to one end of an insulated resistance coil 55 wound upon the electro thermostat, the other end of the resistance being connected to a terminal screw 56 that is normally in electrical contact with the bar of the 120 thermostat upon which the coil 55 is wound. Another insulated lead 57 passes through a passage 58 cut in the key 21 and is electrically connected to a face contact 59 lying flush with the end of the key and being electrically insulated from the key by any suitable material 60. The lead 54 passes through a passage 61 and is electrically connected to a face contact 62 that is insulated 125 from the key by the insulating material 63. 130

When the plunger 23 is depressed as shown at Figure 4 its inclined face forces the contact spring 46 upward and in doing so brings it into electrical contact with the contact spring 47. Upon the underside of the wheel 26 a helical groove 64 is cut and pivotally secured at 65 upon the inner face of the box 20 is a flat metal arm 66 provided with a stud pin 67 adapted to engage with the helical groove 64. One side of the swinging arm 25 is maintained in frictional contact with the free end of the flat metal arm 66 by a spring 25^a the engaging edges being cut or shaped to form an arc described by the radius of the arm 66. The outer end of the arm 25 is stepped upon the side that is in frictional contact with the arm 66 so that as the engaging end of the latter is forced outwardly from the centre of the box 20, by 10 the helical groove being revolved with the wheel 26, and the locking arm 25 forced towards the arm 66 by the spring 25^a the free end of the arm 66 will first engage with the step 68 and later with the step 69. The object in providing for this movement of the locking arm 25 is to allow a coloured section placed upon the rear face of the locking arm 25 to be exhibited through an orifice 70 cut in the base of the box 20 when registering means have reached a predetermined number from the full capacity of calls. This colour remains exhibited until the arm 66 engages with the step 69 when another colour will be exhibited to indicate that the 20 key meter has been used to its full capacity. A portion of the end of the locking arm 25 is turned up to form a flat bolt 71 that projects upwardly between the peripheral face of the wheel 26 and the inner face of the circular wall of the box 20 adjacent to the plunger 23. Cut in the side of the plunger at a point registering with the bolt 71 is a slot 72 into which the bolt 71 will slide simultaneously with the engagement of the 30 free end of the arm 66 with the step 69. This action takes place as the key is withdrawn from the switch after the last call to complete the full capacity of the meter has been made. The engagement of the bolt 71 in the slot 72 prevents the plunger from being depressed again thus making the key useless for conversation until it has been properly re-set. In order to maintain the 40 stud pin 67 in engagement with the helical groove 64 a U-shaped spring 73 is interposed between the inner face of the base of the box 20 and the underside of the arm 66 and to compensate for any rocking movement that such pin may impart to the wheels 26 and 27 a thickness piece 74 is rigidly secured to the inner face of the base of the box on the opposite side of the centre to that occupied by the arm 66. This thickness piece will be in 50 light frictional contact with the underside of the wheel 26.

Referring now more particularly to the switch, in Fig. 1 a table telephone of the automatic type is shown the switch and its electrical connections being housed within a box 75 that is rigidly fixed to and serves as 70 a stand for the telephone 76, the face plate 77 and key way of the switch being conveniently located, in this instance immediately below the dialling device 78 where it is securely fastened to the wall of the box 75. 75 The switch itself is mounted within and upon a suitable metal yoke or frame 79 the extremities of the side members of which are turned outwardly to form brackets 80 to which the parts constituting the lock of the 80 switch are secured by means of screws inserted from the rear of the brackets and engaging in screw hole 81 in the bosses 82 at the rear of the face plate 77 (see Figs. 11 and 11^a). The metal annulus 83 lies upon the brackets 80 and is provided with an annular recess 84 to receive the collar 85 of a barrel 86 the rear end of which is threaded to receive a clamping nut 87 by means of which three cams 88, 89 and 90 are rigidly clamped 90 between it and the shoulder 91. Transversely within the yoke or frame is a divisional plate 92 integral with which is a cylinder 93 that projects forwardly through the barrel 86 and upon which the latter is 95 free to rotate. Rotatably mounted within the cylinder 93 and passing through the divisional plate 92 and the rear of the yoke 79 is a shaft 94, to which is keyed a collar 95 located between the divisional wall 92 and 100 the inner face of the rear of the frame 79. The normal position of the collar 95 is against the rear of the divisional wall 92 where it is maintained by a helical spring 96 that surrounds the shaft 94, its ends being secured, respectively to rear of the yoke or frame at 97 and to the collar at 98. The rear end of the shaft 94 is provided with a flange 100 and secured thereon by means of the central screw 99 is an insulating disc 101 105 the function of which is to make and break certain electrical contacts in a manner that will be hereinafter explained. On the periphery of the collar 95 is a stud pin 102 which normally lies in the angle of a bayonet or L-shaped slot 103 cut in a T-shaped plate 104 secured upon the top of the divisional plate 92 by the screw 105 at one end and a bolt 106 at the other end. The bolt 106 is provided with a sleeve 107 and pivotally mounted upon the bolt 106 above the sleeve is a specially shaped lever 108, the sleeve and the lever being secured in position by the washer 109 and nut 110. The 110 lever 108 is provided with a trigger or catch 111 (see Fig. 13) upon its underside for the purpose of normally holding a plate spring 112 in a raised position the opposite end of such plate spring being secured by the screw 105. The plate spring 112 is specially shaped 115 120 125 130

to partly surround and project beyond the sleeve 107 the projecting portion normally resting upon the trigger 111 as shown at Fig. 13. It is also provided with a side extension 113 (Fig. 14) having a hole 114 in which the pin 102 will lie when the plate spring 112 is released by the trigger 111 and is thereby allowed to occupy the position shown at Fig. 13^a. When the pin 102 is 10 in engagement with the hole 114 the switch is locked and inoperative. The lever 108 is actuated by a relay 115 the operation of which will be hereafter more particularly described.

15 The outer face of the collar 85 lies flush with the outer face of the metal annulus 83 but two oppositely situated segmental sections project slightly beyond these faces to form barrel projections 116 the cut away 20 portions between those projections being adapted to receive key levers 117 of the key-meter. Clamped between the inner face of the wall of the box 75 and the metal annulus 83 is an annular ward plate 118 (interior) 25 having an annular recess 119 upon its rear face to receive the barrel projections 116 and permit them to be freely rotated therein by the key levers 117. Diametrically opposite recesses 120 are cut in the ward plate so as to 30 coincide with the cut away sections between the barrel projections 116 these recesses 120 permitting the key to pass through for the purpose of engaging the barrel projections 116. The formation of the recesses leave two 35 oppositely positioned and inwardly projecting fixed wards 121 that engage with slots 112^a in key 21.

The shaft 94 is capable of a limited longitudinal movement, the spring 96 also permitting a limited rotational movement; the forward end projects beyond the end of the cylinder 93 the projecting portion 123 being rectangular in order that it may enter the orifice 22 in the key when the latter has been 45 turned so as to bring the projection 123 into register with the orifice 22, the spring 96 being stronger than the spring 31 in the key the plunger 23 will be forced in by the projection 123 causing the plunger to function in a manner already described.

50 The cylinder 93 is provided with two longitudinal passages 124 (see Fig. 12^b), a radial passage 125 being cut so as to communicate with each of such passages. The 55 passages 124 and 125 are provided with electric insulating liners 126. The rear ends of the passages 124 are threaded to receive screw plugs 127. Within the liners 126 are spring actuated contact plungers 128 the 60 forward ends of which project a short distance beyond the end of the cylinder 93 while the rear ends are electrically connected to flexible leads 129 and 130 respectively, a compression spring 131 being interposed between each of the screw plugs 127 and the

rear ends of their respective plunger contacts 128. The projecting ends of the plunger contacts 128 are adapted to make electrical contact with the face contacts 59 and 62 when the key is inserted in the switch. 70

In Figs. 6, 7, 7^a, and 8 the key is shown in engagement with the switch in various positions. When the key is inserted in the switch and turned counter clock wise the shaft 94 is depressed and the key levers 117 75 engage and rotate the barrel projections 116, which carry with them the barrel 86 and cams 88, 89 and 90. During the movement of the key through an arc of 135 degrees, the shaft 94 remains depressed and stationary; at that point the projection 123 is caused to enter the orifice 22 in the key and when the key is again moved through a further arc of 45 degrees it also turns the projection 123 and shaft 93 and 80 winds the spring 96; on the completion of the movement of the key through an arc of 180 degrees after the conversation is completed the key may be removed and immediately the projection 123 is free from the 85 orifice 22 the spring 96 unwinds and returns the shaft 94 to its normal position.

In order to assist the operator to be sure that the key is given the requisite amount of rotational movement the barrel 86 is provided with shallow circular recesses or indentations 132 in the same plane and upon the outer surface of the barrel immediately behind the annulus 83. Passing transversely over these indentations 132 is a plate spring 133 the ends of which are suitably secured by the screws 134 to the respective sides of the frame 79. Secured to or formed upon the underside of the spring 133 is a small 95 projection 135 that registers with each of the indentations 132 as they come round thereby causing an audible click.

Upon the peripheral surface of the collar 85 is a notched stop 136 adapted to engage with the toe of a bolt 137 that passes through a radial passage 138 in the annulus 83, the outer end of the bolt being rigidly secured by any suitable means to one end of a curved plate spring 139 the other end of which is rigidly secured upon the peripheral surface of the annulus 83 by means of the screw 140.

There are two of these notched stops 136 situated diametrically opposite one another at a point such that when the switch is in 110 its normal position the toe and the bolt 137 will be engaged with one of the notched stops. The shape of the notch and the toe of the bolt is such as to permit the collar 115 to be rotated by the key 21 through an arc of 180 degrees in each operation in one direction only to ensure that the user cannot turn the key in the wrong direction.

The bayonet slot 103 gives freedom of 120 movement to pin 102 as it makes normal 125 130

movement with the collar 95 and shaft 94. It will be seen from Fig. 14 however that when the key has been inserted in the switch and turned to a position C (Fig. 1) where 5 the projecting end 123 of the shaft has been forced into the passage 22 of the key 21 the key is prevented from being turned in a backward direction either mistakenly or fraudulently because it is in engagement 10 with one side of the longitudinal portion of the bayonet slot 103; the completion of the movement through the arc of 180 degrees must therefore be made once the C position has been reached by the key such movement 15 being possible owing to the direction of travel of the pin 102 taking it along the transverse portion of the bayonet slot 103. The rotation of the shaft 94 through that portion lying between 135 degrees and 180 20 degrees exerts a winding action upon the spring 96 so that when the key is withdrawn from the switch, thus freeing the projecting end 123, the shaft is free to be returned to its normal position by the 25 tendency of the spring 96 to unwind.

The arrangement of the lever 108 and its associated parts are illustrated at Figs. 10, 10^a, 13 and 13^a. The lever is actuated by the movement of the armature 141 of the relay 30 115 which is secured to an adjustable bracket 142 fixed to the side of the frame 79 by screws. The bracket 142 also carries a suitably insulated set of spring contacts one end of one of which 143 extends beyond 35 the others and lies at right angles to the armature 141. Upon the side of contact 143 adjacent to the end of the armature 141 is secured in any suitable manner a block or distance piece 144 adapted to normally hold 40 the contact 143 away from the end of the armature 141. Secured to the other side of the contact 143 by means of the screw 145 is a sheave like member 146 in the annular groove of which the outer end of the lever 45 108 will lie. In its set position the relay 115 will be de-energized and the contact 143 sprung outwardly so that the end of the armature rests upon the side of the block 144 adjacent to it as shown at Fig. 10^a at 50 the same time the free end of the plate spring 112 will be raised and placed upon the trigger 111 so that the perforation 114 lies above and is quite free from the pin 102. When certain electrical circuits are 55 closed so as to energize the relay 115 the armature will drop below the block 144 when the contact 143 will spring in towards the end of the armature 141 and in doing so will move the lever 108 upon its pivot 60 106 causing the trigger 111 to move sufficiently to disengage it from the end of plate spring 112 which will drop to the position shown at Fig. 13^a when the pin 102 will engage in the perforation 114 thus 65 preventing any further movement of the

shaft either longitudinally or rotationally. The action immediately hereinbefore described takes place when a fraudulent key is inserted in the switch and is turned to position C where the extension 123 engages with 70 a passage corresponding with the orifice 22 so that the fraudulent key is effectually locked in the switch and cannot be freed until the plate spring 112 is raised again in order to release the pin 102 from the perforation 114. 75

It will be seen that the sets of spring contacts are in pairs there being one pair in conjunction with and operated by the cam 88 (Fig. 15) four pairs in conjunction with and operated by the cam 89 (Fig. 16) and five pairs in conjunction with and operated by the cam 90 (Fig. 17). 80

In each case one end of the bottom contact of the lowest pair of contacts is extended and bent down to form levers 147, 148 and 149 these levers being adapted to lie normally on the circumferential faces of the cams 88, 89 and 90. 85

One member of each pair of contacts is extended beyond the end of the other member, the extended ends having distance pieces 150 suitably secured between them, in order to maintain them at a fixed distance apart. 90

All the contact springs are provided with two holes through which bolts 151 pass and are electrically insulated from each other by insulating material 152 the three sets being mounted upon the bracket 153 adjustably secured to the frame 79 of the switch by means of the screws 154, the bolts 151 passing through the bracket 153 insulating washer 155, check plate 156, contact springs and insulation pieces, a metal washer 157 being placed on the uppermost insulation piece 152 and the whole clamped together by means of the nuts 158. The check plate 156 underlies the bent lever of each set of spring contacts acting as a support. 100 105

All the spring contacts are provided at 110 one end with contact points 159 arranged to contact in pairs, the other ends of all contacts in each set being adapted for wiring.

A set of spring contacts P. (Fig. 14.) similar in construction to those shown at 115 Figs. 15, 16 and 17 is mounted upon the bracket 160 which is adjustably secured to the frame 79 by means of the screws 161 and are operated by the movement of the insulating disc 101 with the shaft 94, the set being shown in the normal position. 120

The position of the same set of contacts is shown at Fig. 14^a after the key 21 has been inserted in the switch as shown at Fig. 6, the face of the insulating disc 101 having 125 been forced into the position shown by dotted lines at Fig. 14.

A set of spring contacts DR, (Fig. 10^a.) similar in construction to those shown at Figs. 15, 16 and 17 are operated by the 130

movement of the armature 141, as previously explained, the contacts being shown in their normal position. It will be seen that the contact DR⁴ has a contacting point on each face.

The differential relays DR and DR² condensers S and S¹, polarized relay PR, non-inductive resistance NIR and other devices shown on the chart Fig. 18 are ordinary electrical units associated with telephone practice and will be housed in a separate box when used in conjunction with a table set, or contained within the cabinet of a wall set.

When it is desired to use the telephone the calling party will insert the key 21 into the switch as shown at Fig. 6 thus depressing the projecting member 123 of the shaft 94 against the action of the spring 96.

The key will now be turned anti-clockwise, the key levers 117 engaging the barrel projection 116 thus turning the barrel 86 and with it the cams 88, 89 and 90 through an arc of 45 degrees to the position shown at Fig. 7; this will bring the peak 162 of the cam 88 to the position shown at Fig. 15^a raising the lever 147 thereby closing the pair of contacts A¹. The calling party now removes the receiver from the telephone switch hook SH (Fig. 18) allowing the switch hook to make contact through the switch hook springs SH² and SH³ the same movement breaking the bell circuit in which is the ringer BB and condenser S¹. According to present practice for example in the "Strowger" automatic system, as soon as the spring contacts of a switch hook make, the circuit of the line relay of the primary line switch, (not shown on the drawings) associated with the line, is closed over the lead 250. This operates the primary line switch (not shown on the drawings) which in turn operates the secondary line switch (not shown on the drawings) and finally the first selector or equivalent switch in the exchange.

In this invention the primary line switch just mentioned, must be wired so as not to operate until the receiver has been removed and the key inserted in the switch and turned to close the contacts A¹ as its operation is dependent upon a temporary earth being connected to the lead 250, so that if the receiver were removed without the key being inserted and turned to close the contacts A¹ the primary line switch would not operate. This is accomplished by the closing of the pair of contacts A¹ (Fig. 15^a) thus closing the temporary earth contacts A¹ (Fig. 18). The subsequent switches i. e. switches brought into circuit after the primary line switch has been operated are operated via the leads 249 and 250 through the telephone. The calling party then further rotates the key 21 towards the position shown at Fig. 7^a, carrying the peak 162 of the cam 88 past

the bent lever 147 allowing it to return to the normal position Fig. 15 thus breaking the contacts A¹ (Fig. 18) and thereby removing the temporary earth from the lead 250. When the key 21 has reached the position shown at Fig. 7^a the peak 162^a of the cam 89 will have raised the lever 148 so as to operate the set of B contacts closing the pairs of contacts B¹, B², B³ and opening the pair of contacts B⁴ (Fig. 16^a); the circuit is now closed through the lead 250, lead 201, contacts DR⁴ and DR⁵, lead 226, SH², and SH³, lead 225, F and G, lead 202, transmitter T, receiver R, lead 203, PR, lead 204, left winding of DR², leads 205, 206, P³, 209 in parallel with 208, C⁵, 210 then lead 211 and lead 249.

The direction of current is such that PR (Fig. 18) does not operate but the one coil of DR² becomes energized and attracts its armature thereby opening contacts DR^{2e} (Fig. 18). The energization of the coil of DR² is due to the current traversing only one winding thereof thus throwing it out of electrical balance.

The opening of contacts B⁴, removes the short circuit from the dialling switch F, G; it is to be noted that the dialling switch F, G, is only in circuit when the key 21 is in the position shown at Fig. 7^a thus preventing the irregular use of the dialling switch which would be possible without this precaution.

The closing of contacts B³ (Fig. 16^a) enables the receiver and the transmitter to be short circuited when the dialling switch is operated, the current which normally passes through T and R being divided through the contacts B³ and leads 225, 211 and 249.

The reason for this is to enable the switches in the exchange to operate under the most favorable conditions permitted by circumstances and also to prevent the caller from getting disagreeable clicks in the ear.

The closing of contacts B¹ and B² prevent fraudulent use and will be referred to hereafter. The calling party now dials the number required and upon the called party removing his receiver, and announcing himself the calling party is at liberty to turn the key to position shown at Fig. 8 or to the position shown at Fig. 6 in which latter case the key will be withdrawn, no de-registration will have taken place within the key-meter and all the contacts and circuits will resume their normal position (Fig. 18). The effect of the called party removing his receiver will be to reverse the direction of current in the calling telephone. This reversal energizes PR (Fig. 18) thereby closing the three contacts PR¹, PR² and PR³ (Fig. 18). This results in T (Fig. 18) being "shunted out" of the circuit and at the same time a non-inductive "shunt" resist-

ance is placed across R (Fig. 18). The calling party is now in the position that he can hear but cannot speak in reply. As the ordinary receiver can be used as a transmitter, although the efficiency is much lower, the "shunt" resistance is used to prevent conversation being carried on without de-registering the call. If the calling party finds he has been connected to the required 10 number the key 21 will be rotated to the position shown at Fig. 8 and in the course of such movement the peak 162^a of the cam 89 will move from and allow the lever 148 and the B set of contacts to resume their 15 normal position.

Upon the key reaching the position shown at Fig. 8 the peak 162^b of the cam 90 will raise the bent lever 149 thus arranging the contacts C¹, C², C³, C⁴ and C⁵ as shown at 20 Fig. 17^a. The projection 123 of the shaft 94 is now in sectional alignment with the plunger 23 in the key 21 the compressed spring 96 is free to and will force the projection 123 to enter the orifice 22 of the key 21 thereby forcing the plunger 23 into the key thus preventing the key from being turned back, at the same time de-registering the call in the key-meter, as previously explained. The inward movement of the 25 plunger 23 causes the contacts 46 and 47 within the key to be closed and simultaneously (as near as adjustment will allow) the contacts P¹ and P² (Fig. 14) are closed.

The contacts C¹ and C² (Figs. 17^a and 18) 30 are now closed this being necessary in order that the establishment of current through DR and DR² (Fig. 18) will be correctly co-ordinated with other operations.

The contacts C³ (Figs. 17^a and 18) are 35 closed for the purpose mentioned in the next paragraph.

Up to this moment DR² (Fig. 18) has been energized whilst DR has remained de-energized. The operation just described 40 however alters the direction of current allowing it to flow from 249 to lead 212 through the compensating resistance CR, lead 213, left winding of DR, lead 205 and left winding of DR², lead 204 to DR, whilst 45 in the other branch we have current flowing through leads 214, right winding of DR, lead 216, C², lead 217, P², lead 218, switch contacts 128, key contact 62, contact TC, resistance TR and contacts KC, in the key, 50 contact 59 on the key face and contact 128, lead 219, P¹, lead 220, C¹, lead 219 and right winding of DR², leads 222, 223, contacts DR¹ and DR², leads 224 and 204, the 55 current from both branches combining at 55 the terminals of PR and then flowing through PR, lead 203, and PR contacts; R, T, lead 202, dialling switch F, G, lead 225; SH¹ and SH² and C⁴ in parallel; lead 226, contacts DR⁵ and DR⁴, lead 201 to 60 lead 250.

If the circuit is correctly balanced electrically, the windings on each differential relay will neutralize each other, therefore DR is not operated and DR² is de-energized and consequently releases its armature. 70 When DR² is de-energized its armature in dropping back closes through DR² a circuit which short circuits PR, both differential relays and associated key contacts. PR releases its armature allowing the contacts 75 PR¹, PR² and PR³ to open (Fig. 18) thereby freeing the transmitter T and the receiver R. The condenser S it will be noted is also "shunted" out in this operation. The speaking conditions now are exactly the 80 same as obtained in the (Strowger) automatic telephone system.

The contacts C⁴ (Figs. 17^a and 18) are now closed. If these contacts C⁴ did not close it would be possible to break down a 85 connection and establish another by manipulating the switch hook without the key from the position shown at Fig. 8.

The contacts P³ (Figs. 14 and 18) will be opened when the projection 123 of the shaft 94 enters the key orifice, causing the contacts P³ (Fig. 18) to open. These contacts P³ in conjunction with contacts C⁵ normally short circuit the upper winding of DR and the compensating resistance CR. Contacts C⁵ (Fig. 17^a) are opened when the key 21 is in the position shown at Fig. 8.

When conversation is completed the receiver is restored and the key turned forward to complete its movement through an arc of 180 degrees when it will occupy a reverse position shown at Fig. 6 and may be withdrawn from the switch.

The contacts B¹ and B² are for the purpose of preventing the use of a key in which the key plunger has been forced in and fixed in that position with the object of fraudulently obtaining unlimited service. Under these conditions the key contacts 46 and 47 (Figs. 2 and 4) would be closed and as 100 soon as the key had reached the position shown at Fig. 7^a a circuit would be closed through the key which should not normally be the case until the key has been turned to the position shown at Fig. 8, this 105 will bridge the leads 249 and 250 thereby shunting the telephone and causing the current to flow through the thermostat winding 110 55 thus generating heat and causing the thermostat to function and rendering the key temporarily useless.

The result of this fraudulent interference with the key on the lines indicated would be, that whilst the telephone was inoperative the thermostat 45 would be functioning 115 and when the thermostat functioned the telephone would remain unharmed but the key would be entirely useless and would necessitate an expert to re-adjust the various parts thrown out of adjustment.

If through any cause, such as the use of a fraudulent key the circuit for the differential relays is not properly balanced when the plunger is released, the magnets of the relays will become energized and attract their respective armatures, consequently PR (Fig. 18) will keep the transmitter T "shorted" and the receiver R "shunted." The energization of DR (Fig. 18) releases the lever 108 (Fig. 10) thereby locking the shaft 94 as previously explained and preventing any further movement of the key. At the same time contacts DR⁴ and DR⁵ will be opened entirely cutting the telephone out of circuit, whilst contacts DR² and DR are broken thus cutting the key out of circuit; this will prevent tampering or experimenting with different resistance values if such were possible with the key used. It will be noted that immediately the lever 108 is operated by the energization of DR the switch is locked mechanically as previously explained.

Should a subscriber for any reason, such as a faulty service, wish to call an official, it will only be necessary for the key to be turned to the position shown at Fig. 7^a when conversation can be established, the exchange circuits being such that battery is not reversed to the calling line and therefore PR is not operated. When the conversation is completed the subscriber turns the key back to position shown at Fig. 6 when the key may be withdrawn and no de-registration will have taken place within the key-meter. These calls are commonly known as free calls.

All incoming calls are free. The bell rings intermittently as in the usual case. When the receiver is removed the bell is disconnected and conversation takes place. The operation or movement of the switch hook when the receiver is lifted causes disconnection of the ringing current and passage for direct current is established from the lead 249 on the line, contacts C⁵ and P³ in parallel winding of DR² winding of PR, R, T, through F. G. contacts SH³ and SH² of switch hook, contacts 5 and 4 of relay DR to lead 250 of the line. The speech currents pass from the lead 249 of the line through the condenser S. R. T. through F. G. etc., to the lead 250 of the line. The condenser by-path is necessary on account of the impedance which would otherwise be offered by the windings of PR and DR².

I claim:—

1. An apparatus for registering or counting each effective call made upon telephones including a telephone, various electrical circuits connected with the telephone, an electro-mechanical switch for controlling said circuits, and a removable combined key and counter, said key being adapted to engage with the switch and to be moved therein in order to effect various sequential changes in the electrical circuits in such manner that

the operator may make the call and having received a reply, the receiver and transmitter of the telephone are automatically cut out of circuit until the key has been moved to a pre-determined position, cooperating means on the switch and counter for registering the call when the switch has reached this position, and means associated with the switch for completing certain of the electric circuits when the key has been moved beyond said predetermined position, in order to instantly establish conversational conditions.

2. An apparatus as claimed in claim 1 in which the electro-mechanical switch is mounted upon a suitable frame and includes movable means adapted to sequentially open and close said electric circuits, a spring-controlled shaft capable of limited axial and turning movement and provided with operating means, a set of electrical spring contacts actuated by said operating means, means for locking the spring-controlled shaft, a relay in one of said electric circuits adapted when energized to actuate the last mentioned means to lock the spring-controlled shaft, contacts on the face of the switch, cooperating contacts on the face of the key positioned to complete and maintain a circuit through the contacts on the face of the switch as the key is rotated, an electro-thermostat and switch interposed between the contacts on the face of the key, and means within the key adapted to coact with the switch for counting the number of times the key is applied to the switch.

3. Apparatus as claimed in claim 1 including a second telephone adapted, when its receiver is lifted, to automatically reverse the line current in one circuit, a polarized relay energized by the reversal of said line current for short circuiting or shunting out the circuit of the transmitter of the second telephone in order to prevent conversation, a shunt circuit across the receiver of the first telephone arranged to be completed when said line current is reversed, so that the calling party can hear the called party faintly until the key has been moved beyond said predetermined position, and a differential relay controlled by the movement of the key beyond said pre-determined position for the purpose of immediately establishing conversational conditions.

4. Apparatus as claimed in claim 1 in which the key comprises a flat circular shaped closable box, two concentric crown tooth wheels rotatably mounted in said box, the teeth upon one wheel lying radially within the teeth upon the other wheel, a plunger radially and slidably secured within the box, a boss forming a key and provided with an orifice within which the plunger slides, a lever articulated to the plunger and adapted to engage a tooth upon the inner

crown toothed wheel and advance said wheel one tooth when the plunger is moved radially inward, means whereby the articulated lever will engage a tooth upon each of the crown 5 wheels once in every revolution of the inner wheel to move both wheels synchronously one tooth forward, a helical groove in one side of the outer crown tooth wheel, an arm, one end of which is pivotally secured eccentrically to the inner face of the box and provided with a stud slideable in the helical groove, a spring actuated locking arm pivotally secured centrally within the box, such locking arm being shaped so as to enable its 10 movement to be controlled by the eccentrically pivoted arm, steps near the end of the engaging side of the locking arm to permit it to move toward the eccentrically pivoted arm as the latter is carried outwardly 15 by the engagement of its stud with the helical groove, a bolt carried by the locking arm and adapted to lie outside of the periphery of the outer crown toothed wheel, and a notch in the plunger adapted to be engaged 20 by said bolt, synchronously with the engagement of the end of the eccentrically pivoted arm with the outermost step in the locking arm.

5. Apparatus as claimed in claim 1 including means whereby the use of an unauthorized key will cause the key to become locked in the switch and the telephone to be rendered inoperative.

6. Apparatus as claimed in claim 1 in 35 which the combined key and counter is provided with a slideable plunger, a pair of face contacts on the key adapted to close a circuit through the electro-mechanical switch, an electro-thermostat and switch interposed 40 between the pair of face contacts on the key, and coacting means whereby the unauthorized depression of the plunger causes the thermostat to function when the key is moved in the switch, for the purpose herein 45 set forth.

7. Apparatus as claimed in claim 1, comprising means whereby the irregular depression and retention of the operating member of the combined key and counter brings 50 into operation means whereby the telephone is rendered inoperative as the key is moved in the switch associated therewith and thereby renders the key temporarily useless.

8. Apparatus as claimed in claim 1 including a second telephone operatively connected to said circuits, and means enabling the key to be moved to such a position that the sender may ascertain whether the called 55 party will reply, the key being adapted to be moved backwardly and removed from the switch, under such circumstances, without effecting counting, and leaving all parts in such switch and counter in their normal positions.

9. Apparatus as claimed in claim 1 in-

cluding means for preventing the key from moving in one direction when the key is first inserted in the switch.

10. Apparatus as claimed in claim 1 in which the switch includes cams rotatable under the influence of the key, and sets of spring contacts connected to certain of said circuits and adapted to be sequentially operated once in each semi-rotation of the key.

11. Apparatus as claimed in claim 1 in which the switch includes a pair of contacts, a temporary earth circuit adapted to be closed by said pair of contacts, a cam for actuating said pair of contacts when the key is first partially rotated to close the temporary earth circuit pending the operation of the line relay of the primary line switch, the next movement of the key in the same direction causing the cam to release said pair of contacts and permit the same to resume 85 their normal position.

12. Apparatus as claimed in claim 1 in which the switch comprises a frame, a spring operated shaft carried by the frame and capable of limited movement axially and rotatably, the forward end of said shaft projecting beyond the face of the switch and being provided with means to engage with the key after the latter is rotated to a certain position in the switch for the purpose of effecting registration of a call upon the counter, means connected with the shaft to permit the latter to make a limited axial movement, operating members on the shaft, a set of spring contacts adapted to be actuated by said operating members, circuit making and breaking means engageable by the key and adapted to be rotated by the latter independently of the spring operated shaft to a point where the shaft engages with the key and thereafter to rotate in unison with the shaft in one direction only until the key has been turned a pre-determined distance, the key being adapted to be withdrawn at this position for leaving the various parts of the switching readiness for the 95 next operation.

13. Apparatus as claimed in claim 1 in which the switch includes a set of contacts, a plurality of cams adapted to make and break certain of said circuits through said contacts, said cams being rotatable under the influence of the key and each cam being adapted to sequentially operate a separate set of spring contacts once in each semi-rotation of the key so that each cam operates its set of spring contacts and then permits them to return to their normal position before the next cam operates its set of contacts, for the purpose hereinafter set forth.

14. Apparatus as claimed in claim 1 including means whereby incoming calls may be received without the use of the combined key and counter.

15. Apparatus as claimed in claim 1 in-

cluding means whereby when registration is unnecessary, conversational conditions may be established with certain pre-arranged numbers in a telephone system, when 5 the key is turned to a position short of the point when registration of the call is effected, the key thereafter being adapted to be reversely turned to the point of entry and removed so as to leave all parts in their 10 normal positions.

16. Apparatus as claimed in claim 1 including indicating means associated with the key and counter and comprising elements to exhibit a sign when a pre-determined 15 number of calls have been registered.

17. In a telephone system, a first telephone and a second telephone, each having the usual transmitter and receiver, electric circuits operatively connecting said telephones, an electro-mechanical switch associated 20 with each telephone and adapted to control the circuits of the telephone, and a combined key and counter adapted to actuate one of said switches and including elements for registering effective calls only from the 25 telephone having that switch.

In testimony whereof I have signed my name to this specification.

DAVID SOLOMON ELLIS.
